UNITED STATES PATENT OFFICE

ALFRED LIEBERGELD, OF LAUFAMHOLZ, NEAR NUEREMBERG, AND FRITZ SINGER, OF NUEREMBERG, GERMANY; SAID LIEBERGELD ASSIGNOR TO FRITZ SINGER, OF NUEREMBERG, GERMANY

PRESS FOR EXTRUDING SEAMLESS TUBES FROM UNBORED BILLETS OF METALS AND ALLOYS

Original application filed January 9, 1926, Serial No. 80,338, and in Germany January 12, 1925. Divided and this application filed August 2, 1929. Serial No. 383,015.

This invention relates to an improved method of and an improved press for the hot extruding of seamless tubes from unbored metal billets.

5 The present application is a division from Serial No. 80,338 filed January 9th, 1926.

Hitherto in extruding tubes according to Dick's process cylindrical billets have been used, said billets being prepared by complete

10 or part boring on a drilling machine. The use of unbored billets has the disadvantage that the tubes obtained are of irregular thickness owing to insufficient means for accurately guiding the piercing tool.

15 It is true, extruding devices have been known long ago which permit to use also unbored billets. Such known devices consist in the mandrel not being rigidly connected with the punch, but being moved independently of the latter by separate driving means.

20 But such arrangement includes the drawback that separate devices are necessary to control the mandrel piston independently of the punch piston. So not only the contrivances, but also the working method will be complicated considerably, in consequence of which practice preferred to use single working presses and to take into the bargain the boring of the billets.

25 The object of our invention is to provide means which permit a relative movement of the mandrel towards and away from the punch and dispense with separate means for driving and controlling the mandrel.

30 For this purpose the mandrel will be mounted on the main reciprocating member moved by the driving means of the press, whilst the hollow punch guiding the mandrel will be secured to a subsidiary reciprocating member. This subsidiary reciprocating

35 member is arranged on the main reciprocating member in such a manner that it may be slid within certain limits in the same lifting axis as the main reciprocating member to-wards and away therefrom. Means are pro-

40 vided to hold both reciprocating members in their most remote relative position during a

45 part of the stroke so that the punch will touch the billet before the mandrel enters the bil-

50 let, to exert by the intermediary of the punch

a pressure on the billet to fix it rigidly within the container before the mandrel pierces the billet, and to permit the punch to be pushed back by the rising material while the billet is being pierced. Finally means are provided to couple together said reciprocating members in a specific position and to return them into their initial position during the back stroke.

55 By arranging a subsidiary reciprocating member, which is moved partly dependently, partly independently of the movement of the main reciprocating member, but automatically controlled by this movement, the pressing device, according to the invention, permits to 60 execute the steps of fixing the raw billet within the container, the perfectly centrically piercing and extruding of the billet in one single continual operation at the forward stroke of the press.

65 A press embodying the invention is shown in the accompanying drawings.

Referring to said drawings

70 Figs. 1-5 are front elevations of the press being partly in vertical section and showing 75 different stages of the extrusion operation.

75 Referring to Fig. 1, the cylindrical billet *a*, heated to the necessary temperature, is inserted into the bore of the container *b*, the bottom of which is provided with a matrix die *c*. This container *b* is fixed on the table *d* of the uprights *e* of the press, which is shown as a vertical frame, but which might also be arranged horizontally or at any other suitable angle.

80 The crank mechanism of the press, for which an eccentric mechanism might be substituted, comprises a crank shaft *f*, a crank *g*, a connector *h*, a connecting rod *i*, a ball and socket joint *k*, which may be constructed as a 85 pivot joint and a reciprocating guide-piston *l* for guiding the connecting rod. A perforating mandrel *m* is fixed in the bottom of the piston *l* and its diameter corresponds to the inner diameter of the tube to be extruded.

90 The punch *n*, which is hollow and concentrically surrounds the perforating mandrel *m*, is fixed in the end face of a freely movable plunging piston *o*, the inner surface of which 95 serves to guide the piston *l*, said plunging

piston being guided in the uprights *e* on its outer surface. The guiding piston *l* with the mandrel *m* is positively moved from the crank mechanism. The plunging piston *o* with the punch *n* is positively moved by means of driving devices in the same axial direction as the piston *l* and intermittently controlled in accordance with the operations.

Special mechanical devices and the movement of the material to be perforated serve as driving means. The mechanical driving means consists of a cam disk *p* keyed on the crank shaft and having a contact face *p'* which acts upon a roller *q* mounted in a transverse bridge *r*. The bridge is fixed in the open end of the plunging piston *o* so that said roller can be easily rotated. Instead of the cam disk mechanism described a toggle lever mechanism or a controlling grooved disk gear can be used.

The press operates as follows:

Fig. 1 shows the position of the driving mechanism, the pistons and the rams prior to the starting of the press in the upper dead center position. The piston *o* is suspended by its bridge *r* on the piston *l* and descends with the same. After the punch *n* has come in contact with the billet *a* the piston *l* alone continues the descend. The contact face *p'* of the cam disk *p* comes into contact with the roller *q* and lowers the same and the piston *o* with the punch at slow speed until the billet has completely filled the gap between the punch and the die *c*.

35 The preliminary pressing of the billet *a* is completed at the moment at which the cam disk *p* moves away from the roller *q*. The punch *n* rests for a moment on the preliminarily pressed billet *a* without exerting any 40 movement and without exerting any further pressure than that of its own weight and that of the plunging piston *o*.

As shown in Fig. 3 the mandrel *m* which continues its descending movement now perforates the billet. The material displaced by this step makes the billet *a* longer whereby the punch *n* together with the plunging piston *o* are pushed slightly upward. Only a small portion of the material displaced by the 50 mandrel *m* drops as a slug *s* through the bore *t* of the working table *d* which is designed to receive the finished tube *u*.

As shown in Fig. 4 the guide piston *l*, continuing to descend, directly contacts, after the piercing has been completed with the bottom plate of the plunging piston *o*, so that the two pistons *l* and *o* and the two punches *m* and *n* will, from this moment, descend together and press out the material of the billet in the shape of a tube *u* through the ring-shaped opening *v* (Fig. 4a) which is formed between the stationary die *c* and the descending mandrel *m*. At the end of the stroke the 65 preliminary treatment of the billet *a* and the

tube extrusion are terminated and the crank *g* is at the lower dead center position.

At the return stroke crank mechanism *f*, *g*, *h*, *i*, *k*, *l* will the mandrel *m* move back according to Fig. 5 until the guide piston *l* which guides the connecting rod comes into contact with the bridge *r* which carries the roller, so that from this moment the plunging piston *o* with the punch *n* is drawn along and returns into the initial position to which the cam disk *p* has also returned. In Fig. 5 the elements are almost in the initial position in which they are shown in Fig. 1.

The tube *u* which is still connected with the residue *w* from extruding is then severed in a manner known per se, whereupon the tube and the residue from extruding can be removed.

Instead of the guide piston and the plunging piston engaging the one with the other, 85 pistons may be used for the punch and the mandrel which move side by side.

We claim:

1. A press for extruding seamless tubes from unbored billets of metals and alloys, comprising a main reciprocating member, a perforating mandrel secured on said member and guided in a hollow punch, said punch being secured on a subsidiary reciprocating member which is guided in the press frame and mounted on the main reciprocating member adapted to be slid within certain limits in the same lifting axis as the main reciprocating member towards and away therefrom, means to hold both reciprocating members in their most remote relative position during a part of the stroke to effect a pressure on the billet by the punch when the latter touches the billet and to permit the punch to be pushed back by the rising material while the billet is being pierced, means to couple together said reciprocating members in a specific position, so that both members finish together the remainder of the working stroke, and means to return both reciprocating members into their initial position during the back stroke.

2. An upright press for extruding seamless tubes from unbored billets of metals and alloys comprising a main reciprocating member, a piercing mandrel secured on said member and guided in a hollow punch, said punch being secured on a subsidiary reciprocating member guided in the press frame and suspended on the main reciprocating member, said subsidiary reciprocating member being adapted to be slid within certain limits in the same lifting axis as the main reciprocating member towards and away therefrom to press on the billet by its own weight and by the weight of the punch and to be pushed back by the rising material while the billet is being pierced, means to couple together said reciprocating members in a specific position, so that both members finish 120

together the rest of the working stroke, and means for returning both reciprocating members into their initial position during the back stroke.

3. A press for extruding seamless tubes from unbored billets of metals and alloys comprising a main reciprocating member driven by mechanical means, a piercing mandrel secured on said member and guided in a hollow punch, said punch being secured on a subsidiary reciprocating member, guided in the press frame and mounted on the main reciprocating member, said subsidiary reciprocating member being adapted to be slid within certain limits in the same lifting axis as the main reciprocating member, towards and away therefrom, cams for operating said subsidiary reciprocating member by means of rollers, said cams being driven by the same driving shaft as the main reciprocating member and including a movement adapted to drive the subsidiary reciprocating member, before the mandrel contacts with the billet, until it presses thereon, and to allow the punch to be pushed back while the billet is being pierced, means to couple together said reciprocating members in a specific position, so that both members finish together the rest of the working stroke, and means during the back stroke to return both reciprocating members into their initial position.

4. A press for extruding seamless tubes from unbored billets of metals and alloys, comprising a main reciprocating member shaped as a piston, mechanical means for operating said piston, a shank embodying a mandrel portion secured on said piston and guided in a hollow punch, said punch secured on a subsidiary reciprocating member shaped as a closed end cylinder and guided in the press frame, said cylinder surrounding and guiding the first named piston and adapted to be slid within certain limits towards and away from the quoted piston, cams for operating the cylinder by means of rollers, said cams driven by the same driving shaft as the piston and including a movement adapted to drive the subsidiary reciprocating member, before the mandrel touches the billet, until the punch presses the billet, and to allow the punch to be pushed back while the billet is being pierced, a bottom in the cylinder by which the piston and the cylinder are coupled when the piston contacts with said bottom, and a carrier mounted on the cylinder, adapted to carry back the cylinder into its initial position, when the piston returns to its initial position.

5. An upright press for extruding seamless tubes from unbored billets of metals and alloys, comprising a main reciprocating member shaped as a piston, a crank gear for operating said piston, a shank embodying a mandrel portion secured on said piston and guided in a hollow punch, said punch secured

on a subsidiary reciprocating member shaped as a closed end cylinder and guided in the press frame, said cylinder surrounding and guiding the first named piston and adapted to press on the billet by its own weight by the intermediary of the punch and to be pushed back by the rising material while the billet is being pierced, a bottom in the cylinder by which the piston and the cylinder are coupled when the piston contacts with said bottom, and a carrier mounted on the cylinder, adapted to carry back the cylinder into its initial position.

In testimony whereof we affix our signatures.

ALFRED LIEBERGELD.
FRITZ SINGER.
